Symonoff & Lechner

ATTORNEY

UNITED STATES PATENT OFFICE.

JOHN H. STORY, OF MERCHANTVILLE, NEW JERSEY.

TIMER.

Application filed December 6, 1919. Serial No. 343,076.

To all whom it may concern:

Be it known that I, JOHN H. STORY, a citizen of the United States, residing at Merchantville, in the county of Camden and 5 State of New Jersey, have invented certain new and useful Improvements in Timers, of which the following is a specification.

This invention relates to timers such as used on the Ford automobile and it has for 10 one of its primary objects the provision of an improved timer which is much cheaper in construction and will have a greater life than the standard types of timers ordinarily used.

15 Among the more specific objects of my invention are the provision of a metallic race for the timer brush or roller in place of the fibre race which is customarily employed; and the provision of a novel arrangement of 20 the contacts with such metallic race whereby the contacts are insulated from the race.

The foregoing, together with such other objects as may hereinafter appear or are incident to my invention I obtain by means 25 of a construction which I have illustrated in preferred form in the accompanying drawings, wherein

Figure 1 is a view looking into the face of a timer embodying my invention; Figure 2 30 is a section taken on the line 2—2 of Figure 1; Figure 3 is a section taken on the line 3—3 of Figure 1; Figure 4 is a view similar to Figure 1 illustrating a modification of my invention; and Figure 5 is a section taken 35 on the line 5—5 of Figure 4.

Referring now to Figures 1, 2 and 3 the reference numeral 7 indicates the timer shell or housing provided with an arm 8 for connection with the spark lever, said shell being 40 apertured for the reception of the four binding posts 9 which are insulated from the shell and positioned by the sleeves 10 and 11, when the nuts 12 are drawn up, as will be readily understood from inspection of Figure 2. At their inner ends the binding posts 45 are provided with the shoe or contact pieces 13. Within the shell is located a washer-like metallic member 14 which may be secured in place by any preferred means such as are shown for example in Figure 3 at 50 15. The washer 14 is provided with four apertures 16 within which the contact pieces 13 project, the faces of the contacts and the member 14 being substantially flush.

55 The timer shaft is indicated at 17 and it

carries the brush A which, in the present showing, is of the wipe contact type. It will of course be understood that the ignition wires lead to the binding posts 9 and are secured thereto by means of the nuts 18 in 60 the usual manner.

Especial attention is directed to the size of the contact pieces 13 with reference to the apertures 16, which latter are sufficiently large to provide an insulating gap around 65 the contact pieces such as will not be bridged by the current.

This construction has the following advantages:—The plate 14 presents a much superior surface for the brush to ride on 70 for the reason that it does not wear out as rapidly as the fibre and is not affected by the lubricant which softens the face of the fibre races, the softened material being carried by the brush onto the contacts, frequently causing faulty firing. The life of 75 the race is therefore obviously much longer than the fibre races and no difficulties such as those noted are encountered.

It will be apparent that the metallic race 80 may be cast or stamped integral with the shell and in Figures 4 and 5 I have shown a construction in which these parts are cast integral. In this construction I have also shown the contact pieces 13 as insulated from 85 the race 14 by insulating sleeves 19. This construction is also advantageous for the reasons above noted and in addition it is to be observed that the insulating sleeve presents but a relatively small area to the brush 90 and therefore the liability of faulty firing by reason of the spreading of the fibre over adjoining surfaces is reduced to a negligible factor. In contradiction to this, in the ordinary construction, of the total surface presented to the brush, a large portion is fibre.

It will be obvious that various other embodiments of my invention may be made and that the invention as defined is not limited to the precise structure shown.

I claim:

1. The combination in a timer of a timer shaft, a rotating brush, an annular race composed of hard material such as metal on 105 which the brush rides, said race being disposed at approximately right angles to the axis of the shaft and being provided with apertures, and a plurality of contacts projecting into said apertures from a direction substantially parallel to the axis of the shaft 110

and lying approximately flush with the race.
2. The combination in a timer of a timer shaft, a rotating brush, an annular race composed of hard material such as metal on which the brush rides, said race being disposed at approximately right angles to the axis of the shaft and being provided with apertures, and a plurality of contacts projecting into said apertures from a direction substantially parallel to the axis of the shaft and lying approximately flush with the race, said apertures being sufficiently larger than the contacts to provide a space about the contacts of material extent.

3. The combination in a timer of a timer shaft, a brush, a timer shell provided with an annular race disposed at approximately right angles to the axis of the shaft and having a plurality of apertures, contact members materially smaller in cross section than the apertures extending through the shell into said apertures and lying approximately flush with the race, and insulating material in the space about the contact members.

In testimony whereof I have hereunto signed my name.

J. H. STORY.
